TOY FIREBOAT

George Greenberg, New York, N.Y.

Application August 14, 1946, Serial No. 690,369

6 Claims. (Cl. 46—93)

1

This invention relates to toys, and has for its main object to provide a toy boat which imitates in appearance and action the usual well known fire boats.

Another object of this invention is to provide a toy of the mentioned character which will have means to propel the same, and means to throw a water stream, or do both, at the same time, at the will of the child playing with the toy.

Still a further object of my invention is to provide a device, as indicated hereinbefore, in which all the operations will be provided for with power, and controlled from a single motor, arranged in a novel, efficient way, and having novel, efficient coupling means for the various operations.

Still further objects of this invention will be apparent as the specification of the same proceeds, and, among others, I may mention to provide a device of this type which will be simple in construction, comparatively inexpensive to manufacture, easily operated, and which will have a novel pump device and a novel rudder, conducive to a novel and entertaining operation incorporated therein.

In the drawings forming a part of this specification, and accompanying the same:

Fig. 1 is a diagrammatical sectional view of a toy fire boat, constructed according to my invention, parts of the same being broken away;

Fig. 2 is a diagrammatical plan view of the same, portions of it being shown in section therein;

Fig. 3 is a sectional view, the section being taken on the line 3—3 of Fig. 2, and

Fig. 4 is another sectional view, being taken on the line 4—4 of Fig. 2;

Fig. 5 shows a detail for fixing the rudder in a desired position, and

Fig. 6 is a diagram showing the automatic running of the ship when the rudder is set and fixed at a certain angle.

Referring now to the drawings more in detail by characters of reference, the numeral 10 indicates my novel toy fire boat, in general, having the hull 11, preferably made of sheet metal, the deck 12, an imitation smoke stack 13, a rudder 14, and the propeller 15.

For the driving power for my toy ship, I arrange a spring motor at about the center of the ship, diagrammatically shown in the section of Fig. 1, and generally indicated by the numeral 16. A winding shaft 17 with a winding grip 18 is also shown over the deck of the ship, all these devices being shown generally in a diagrammatical manner, as they may be of any constructions well known in this art.

Any usual means, generally indicated by the numeral 19, may also be employed to normally stop the running of the spring motor 16 when it is wound up for operation, said means 19 being adapted to be moved into a position where they will release the spring motor 16 and permit its operation. One of such well known means may operate by the indicated pin 19a and its button 19b, so that, when the pin is pushed inwardly, the spring motor is locked, and when it is pulled outwardly, the spring motor is released.

15 The spring motor may have a throughgoing shaft, the left hand end of the same projecting from the housing of the motor, and being indicated at 20, while the right hand end is indicated at 21. A conical friction clutch member 20a is secured on the shaft end 20, and a similar clutch friction cone 21a is secured on the shaft end 21. A propeller driving shaft 22 is journaled in an appropriate manner in the rear portion of the boat, carrying at the outer free end thereof, at the stern of the boat, the drive propeller 15.

20 A slideable clutch member, generally indicated by the numeral 23, is arranged on the inner end of the propeller shaft 22, the same having a front female friction cone 24, which may engage the male friction cone 21a at that end at that side of the spring motor 16, when the sliding clutch element 23 is moved inwardly, as indicated by the arrow 25.

25 An operating arm 26 is provided for the clutch 23, pivoted in the frame member 27, as at 28, its lower end 29 engaging a conical channel 30 in the clutch member 23, said lower end 29 being fork-shaped, so as to permit the rotation of the clutch member 23, and still be adapted to engage the same for moving it inwardly or outwardly.

30 The clutch member 23 is longitudinally slideable on the shaft 22, but it is secured thereon in such a manner, that the rotation of the shaft 22 will be transmitted to the clutch member 23 or vice versa, as it is well known in this art.

35 It will be seen that, when the arm 26 is turned outwardly from the center of the boat, as indicated by the arrow 28, and as shown in Fig. 1, its forked lower end 29 will push the clutch member 23 in a left hand direction, as indicated by the arrow 25, and said clutch member will drivingly connect the spring motor shaft 21 to the drive shaft 22 for the propeller, and in such

2

a position of the parts described, the boat will be driven by the propeller 15.

A guiding and locking frame device 31 is built on the deck 12 for the arm 26, said device having a top 32 with a slot 33 therein, in which the arm 26 may be moved in a left hand or right hand direction. A transverse slot 34 is provided for the outer portion thereof, and normally the arm 26 will have a tendency, by the resilient nature of its own material and by its formation, to snap into said slot 34, thereby locking in its right hand position, as shown in Figs. 1 and 2.

When it is desired to release propeller 15 from the motor 16, arm 26 will be bent out of its limiting transverse slot 34, arrow 35 (Fig. 2), and then moved in a left hand direction, opposite to the arrow 28, and permit it to snap into the left hand limiting transverse slot 36, whereby the same will be locked in its left hand innermost position.

It will be apparent that moving the arm 26 in a left hand direction, will move the clutch member 23 in a right hand direction, opposite to that shown by the arrow 25, and will disconnect the clutch cones 21a and 24.

When it is desired again to start the propeller 15, arm 26 will be slightly bent to escape from the limiting slot 36, and moved to its right hand position, effecting the locking of the clutch.

A water pumping device, generally indicated by the numeral 37, is arranged in the front of the boat, raising the water through the pipe line 38 above the deck, and expelling it through the fire nozzle 39.

A driving shaft 40 is arranged for the pump 37, the arrangement of said shaft, its journaling and its connection to and disconnection from the spring motor 16 being identical to those described for the propeller shaft 22, but said devices being arranged in the front of the boat, and generally in an opposite direction to the devices for the propeller shaft 22. A slideable clutch member, generally indicated by the numeral 41, is arranged on the shaft 40, however rotatable therewith, as will be understood and it terminates in a female clutch cone 42. The clutch member 41 may be moved to its innermost right hand or outermost left hand positions, by an arm 43 pivoted in the frame member 44, as at 45, and having a forked lower end 46, engaging the cone channel 47 in the clutch member 41.

One method of arranging the cone members 23 and 41, on their respective shafts, in a longitudinally slideable, but rotatably secured manner, is shown in connection with the pump drive of my device at the left hand side of Fig. 1. Clutch member 41 may have a hollow tubular front part 48, in which are arranged two longitudinal slots 49, and a transverse pin 50 is secured into the shaft 40, the two ends thereof being slideable in the slots 49. It will be obvious that in this manner the rotation of the shaft 40 will be transmitted to the clutch member 41, but said member may still slide inwardly or outwardly on said shaft.

A guide and locking structure, generally indicated by the numeral 51, may be arranged for the arm 43, being identical to the guide and lock structure 31, for the arm 26, described hereinbefore.

In the embodiment of my toy fire boat shown in the drawings, I employ a specific pump device 37. In said device, a cone shaped tube 52 is arranged in the front of the boat. This tube is rigidly connected with the casing 53 of pump

31, and serves as an inlet, into which the water is forced as indicated by arrow 54a, when the ship is in forward motion, thus adding to the performance of the pump. Secured on the end 5 of the shaft 40 is the impeller 54, a rotational body so shaped that the axially entering water is diverted radially along the impeller blades 55. Upon rotation of said impeller, water will be ejected from the impeller by centrifugal force, and this flow of water passes through the stationary discharge blades 56, where additional pressure is being created in the water, and a circular flow in volute 57, as well, where the direction of flow corresponds with the rotation of the impeller, as indicated by arrow 58. Stationary parts 53, 56, 57 and base 59 are parts of the pump casing, as it is well known in this art. The water from said volute is pressed upwardly into the tube 38 for the fire extinguisher nozzle 39. The nozzle 39 may be appropriately narrow, so that a comparatively strong water spout or stream 39a will emerge from the same and will be thrown to a substantial distance. The nozzle 39 may be made rotatable, by any appropriate means, so that the stream may be directed into a desired direction.

As has been mentioned, a rudder 14 is also employed at the stern of my boat, the same being secured on a depending vertical shaft 60, which is rotatable in its housing 61, and may be turned from the deck through the arm 62. A plate member 63 is secured on the frame 61, having a plurality of holes 64 arranged in a circular manner, and an aperture or hole 65 is provided in the arm 62.

After the rudder 14 has been turned into a desired direction through the arm 62, the same will be fixed in its position by passing a pin 66 through the aperture 65, and through a corresponding hole 64. In this manner, the boat may be set into a desired direction, and, if permitted freely to sail, ultimately it will make a complete circle.

In Fig. 6, such a course of the boat is illustrated diagrammatically, and in said figure, 70 is the shore line, 71 is the water, 72 is my toy boat, and arrows 73 indicate the direction of the sailing of the boat, if permitted to run freely.

According to the setting of the rudder 14, the boat will make a complete circle, larger or smaller, and return to the starting position 74. Two of these circles are indicated at 75 and 76.

A pin 66 may be secured to the frame 61 by flexible member 77, as by a cord or chain, and a ring 78 may also be employed on it for easier handling.

Such a toy boat obviously must also be made substantially watertight, as otherwise it soon may founder.

In my embodiment, illustrated in the drawings, only one place is left where water may leak into the hull, and it is at the exit of the propeller shaft from it indicated at 80.

For simple inexpensive means to prevent an entrance of the water at that place, I employ a stuffing box 81, having a sleeve 82 and a gland 83 adapted to be set by screw threading, as will be obvious. Cotton waste and solid grease may be employed in sleeve 82 and compressed by gland 83. This gland also serves as a bearing for shaft 22.

An appropriate screen may also be employed at the front open end of the water inlet tube 52 for the pump device. It may have any usual construction, well known in this art, (not shown), whereby dirt and other injurious material will be

prevented from entering into the machinery and piping.

It will be understood that the toy can be used outdoors, as on a lake or swimming pool, etc., but it may be used even in a bathtub at home, which is one of the desirable qualities of my invention.

In Fig. 2, the bow and stern of the ship have been broken away for clearer showing of my construction, but their upper outlines are indicated in an imaginary manner by the respective dot and dash lines 90 and 91.

I also show the railing 92, which may be added to my toy to effect a more realistic impression. With reference to the couplings or clutches shown in the drawings, and explained hereinbefore, I may mention that the same are supported in two places on the driver shaft, when in an inoperative position, and this feature insures a registering position with the driver shaft when the clutch will be put into operation.

It also will be understood that the driver shaft on the pump side may have a much higher speed than the driver shaft for the propeller on the other side, as the pump needs higher revolutions per minute than the propeller. This can be arranged in connection with the spring motor by adding different transmission gears to the two sides, as will be understood by those versed in this art.

On the pump side, the conical surfaces of the clutch device may not be the serrated ones indicated, but they may be smooth, as for instance, made of an appropriate hard wood. With this construction, gradual engagement will be insured between the cone surfaces, as the pump clutch is put into operation, which is desirable in view of the higher rate of revolution for the pump.

The feature that the switch arm 43 can be placed into an extreme locking position, and then locked, will insure a sufficient pressure between the clutch heads 20a and 42, and thereby a reliable connection will be made between the two shafts 20 and 40, even when the friction surfaces are smooth, while then the process of engagement of the clutch will be gradual and without a shock.

While I have shown a preferred embodiment of my invention, it is to be understood that changes and variations may be resorted to in the elements, construction and combination of my invention, and I reserve my rights to such changes and variations as are within the spirit of this specification, and the scope of the claims hereunto appended.

What I claim as new, and want to protect by Letters Patent of the United States, is:

1. In a toy fire boat, a hull with a deck, a motor in the hull, means to control the motor from the deck, a shaft driven by said motor and projecting from it, both forwardly and rearwardly, a clutch member at each end of the shaft, a rotary pump in the hull in front of the motor, an intake for the pump wherethrough the same is adapted to draw from the water on which the toy is floating, a water ejector pipe from said pump to above the deck terminating in a nozzle in imitation of a fire boat, a driving propeller in the rear of the hull, a shaft for the pump, and a second shaft for the propeller, a slidable clutch member on the inner end of each, the pump and the propeller shafts adapted to cooperate with the respective clutch members on the motor shaft, a pivoted operating lever for each slidable clutch

member projecting above the deck, an upstanding frame element on the deck for each operating lever having a slot wherein said lever may slide in both directions, said slot terminating in a transverse enlargement at each end, whereby, upon turning the respective levers in one or in the other directions, the pump, respectively the propeller, may be operatively connected to or disconnected from either of its positions, and said levers may be temporarily locked through the use of said termination enlargements in said slot.

2. In a device, as set forth in claim 1, a control member for said motor adapted to start or stop its operation as desired, said member projecting over the deck.

3. In a device, as set forth in claim 1, said intake for the pump opening towards the front of the boat whereby upon the sailing of the boat the inrushing water will aid in the operation of the pump.

4. In a device, as set forth in claim 1, a rudder at the stern of the boat having a rotatable shaft projecting above the deck thereof, means on the deck to turn said shaft and the rudder thereon and to temporarily secure it in any of its various positions, said motor being spring operated, a winding shaft for the same, a starting and stopping member for it, each projecting above said deck whereby the boat may be set in various conditions, and whereby all the necessary settings for various conditions may be operated from the deck independently of one another and may be locked on the deck in any of their selected positions.

5. In a toy fire boat, a hull with a deck, a motor in the hull, means to control the motor from the deck, a shaft driven by said motor and projecting from it, both forwardly and rearwardly, a clutch member at each end of the shaft, a rotary pump in the hull in front of the motor, an intake for the pump wherethrough the same is adapted to draw from the water on which the toy is floating, a water ejector pipe from said pump to above the deck terminating in a nozzle in imitation of a fire boat, a driving propeller in the rear of the hull, a shaft for the pump, and a second shaft for the propeller, a slidable clutch member on the inner end of each, the pump and the propeller, shafts adapted to cooperate with the respective clutch members on the motor shaft, and a pivoted operating lever for each slidable clutch member projecting above the deck.

6. In a toy fire boat, as set forth in claim 5, the intake for said pump being directed forwardly in front thereof through the bow of the boat, whereby upon causing the sailing of the boat and the operation of the pump, said operation will be aided and strengthened.

GEORGE GREENBERG.
